[57] **ABSTRACT**

A sewing machine equipped with a pulse generating means capable of providing digitally coded signal pulses related to the angular position of the sewing machine main-shaft is disclosed. The total number of coded signals exceeds the number of angular position sensors employed. The preferred embodiment utilized two Hall effect devices to provide four binary coded signals responsive to the position of the sewing machine mainshaft.

SEWING MACHINE EQUIPPED WITH PULSE GENERATOR

BACKGROUND OF THE INVENTION

The present invention relates to sewing machines which are equipped with a pulse generator for producing digitally coded signals responsive to the sewing machine main-shaft.

Known sewing machine driving units of the mechanical type generally coupled the sewing machine pattern cams, needle and needle bar to the main shaft by gears and/or belts. Therefore, the problem of synchronizing the main shaft driving unit, and the pattern cams is minimized and performed in a conventional manner. However, more accurate synchronization is required for sewing machines that incorporate a needle-up or needle-down stopping function and/or a thread trimming operation. These sewing machines require systems that provide accurate signals responsive to discrete positions of the sewing machine main shaft and heretofore have been subjected to frequent maintenance and adjustment to keep them in proper working order. Mechanical position sensors, which sense the position of the main shaft, are subject to fatigue since the moving parts wear out with constant use of the sewing machine. Static sensing devices which utilize light beams and photoelectric sensors have not been entirely satisfactory since the lint laden atmosphere surrounding the sensors frequently causes the sensors to become covered with lint and dust, thereby reducing the sensitivity and accuracy of the sensor, again requiring frequent maintenance.

Other known position sensing devices, used with electromechanical driving units for sewing machines, include, a permanent magnet affixed or coupled to a sewing machine main shaft cooperating with an electric sensor, which provides a pulse each time the permanent magnet passes over a gap provided in the electromagnet's core. Other devices known in the art, utilize a rotating magnet and stationary Hall effect devices to sense and provide a pulse each time the permanent magnet becomes proximate the Hall device. Still other devices utilize an electromagnet which has a core provided with an air gap. A non-flux conducting disc, provided with openings therein, is affixed or coupled to the main shaft of the sewing machine and placed in the air gap of the electromagnet. When the nonflux conducting portion of the disc is within the air gap of the electromagnet the flux lines are broken and the inductance of the electromagnet decreases. When the disc rotates so that the opening of the disc is within the air gap of the electromagnet the inductance of the electromagnet increases. This change of state of the electromagnet may be used directly or indirectly, e.g., to control the feedback of an oscillator, thereby yielding an output which is related to the position of the shaft. In addition, known in the prior art, are spirally shaped permanent magnets, which are affixed to a shaft proximate a Hall device. Rotating the shaft changes the output or state of the Hall device in varying amounts relative to the position of the shaft upon which the magnet is affixed. Generally, the prior art devices require that the permanent magnet device be affixed to the rotating shaft, or that the flux lines of the magnet be cut to effect a change in state of the sensor. All of the sensors of which we are aware provide a signal responsive to discrete

positions of a rotating member, however, none of the prior art systems, to our knowledge, utilizes a plurality of position sensing devices, or pulse generators, or a stationary permanent magnet and stationary Hall effect devices, proximate thereto, to provide coded digital signals responsive to discrete positions of a rotating member and the direction of rotation thereof.

SUMMARY OF THE INVENTION

10 A sewing machine having a signal generator utilizing the principles of the present invention overcomes the shortcomings of the prior art by providing synchronizing pulses that are binary coded and are responsive to discrete positions of the sewing machine main shaft and its direction of rotation thereof. The signal generator of the present invention is reliable and essentially maintenance free.

20 A sewing machine, in accordance with the principles of the present invention, comprises stitch forming instrumentalities including a needle carrying bar, actuating means including a main-shaft operatively connected thereto, means for controlling the stitch forming instrumentalities, and a pulse generator means providing digitally coded signal pulses related to preselected angular positions of the main-shaft for synchronizing the controlling means with the main-shaft.

25 Additionally, in accordance with the principles of the present invention, a sewing machine may include a pulse generator for providing binary coded digital pulses relating to the angular position of a rotating member comprising, a base member, permanent magnet means adapted to be affixed to said base member, at least two sensor means adapted to be mounted juxtaposition the permanent magnet means for providing output signal pulses, the sensor means having two stable states, and at least two rotating position indicating means carried by the rotating member each having a stepped peripheral circumference cooperating with the sensor means for changing the state of the sensor means in accordance with preselected angular positions of the rotating member.

BRIEF DESCRIPTION OF THE DRAWINGS

30 The invention will now be described with reference to the accompanying drawing of a preferred embodiment in which:

35 FIG. 1 is a front elevational view, partly broken away, of a sewing machine in which the present invention has been incorporated;

40 FIG. 2 is an enlarged perspective view of a pulse generator built in accordance with the principles of the present invention;

45 FIG. 3 is a diagrammatic elevational view of the pulse generator showing the paths of the flux lines;

50 FIG. 4 is a front elevational view of a pair of cams aligned on a shaft to provide the signal output pulses that results in the truth table shown in FIG. 5; and

55 FIG. 5 is a truth table showing the signal output state of the Hall sensors just prior to and after activation by the proximity of the high portion of a cam.

DESCRIPTION OF THE PREFERRED EMBODIMENT

60 Referring to the drawing, and in particular to FIG. 1, the invention is disclosed as being embodied in a sewing machine 10. The sewing machine 10, in which the present invention is incorporated, includes a frame 11

which has a substantially rectangular hollow base 12, having at its upper side a work supporting surface or bed 14, including therein a throat plate 16. Suitably secured upon the hollow base 12 is a vertically disposed hollow standard 18 which carries an overhead bracket arm 20 terminating in a hollow head 22 in which is journaled a reciprocating needle bar 24 carrying a needle 25. Also included in the hollow head 22 is a presser bar 26 which is terminated in a presser foot 28. Additionally included within the sewing machine frame 11 is an electrical drive motor 33 which is carried in the base 12. The motor 33 is coupled, via a pulley (not shown) and a belt coupling means 37, to a drive shaft 39. All of the mechanisms mentioned above are found on a conventional sewing machine, as well as stitch forming instrumentalities 42 and work feeding mechanisms, not shown, which cooperate with the needle 25 and are coupled to the drive shaft 39, via a second belt coupling means 40 and gears 52, 54 and 56, 58 respectively, all well known in the art. Shaft 46, which is coupled to the work feeding mechanisms, not shown, is designed in the preferred embodiment of the present invention to be driven in synchronism with the main shaft 39 with a one-to-one speed ratio. Hereafter, when reference is made to stitch forming instrumentalities it will be understood to include all conventional mechanisms that relate to forming a stitch pattern, e.g., work feed, light, etc.

A preferred embodiment of a contact-free pulse generator 43 of the present invention is shown in an enlarged perspective view in FIG. 2 and includes semicircular shaped cams 50 and 52 affixed to a shaft 46 and retained thereon by screws 48. The cams 50 and 52 have a variable (stepped) peripheral circumference 54 and 56, respectively. The circumference 54 and 56 are adapted to cooperate with Hall effect devices 58 and 60, respectively.

The Hall effect devices 58 and 60 in the preferred embodiment of the invention are a standard part No. 1SS4 manufactured by the Microswitch Division of Honeywell. Included in the Hall device in addition to a Hall sensing element is a threshold detector that provides a fixed output voltage when the Hall sensing element exceeds a minimum voltage value across its terminals in the presence of lines of flux. Hereafter, when reference is made to a Hall device it will be understood to include both a Hall sensing element and a threshold detector. Thus, the Hall devices 58 and 60 provide an output voltage of approximately 4 volts when the south pole of a permanent magnet is proximate a prescribed portion of the surface 62 and 64 of the devices 58 and 60, respectively. Removal of the magnet or reducing the lines of flux proximate the surface area provides a low level output voltage of approximately 0.3 volts. The Hall effect device described provides the aforementioned voltages across leads 70, 70' and 72, 72' when a D.C. voltage of +5 volts is provided at input leads 66, 66' with leads 68, 68' being retained at a reference ground potential.

Hereafter, in this specification the low output voltage level of 0.3. volts will be referenced to as a 0 condition and the 4 volt output voltage or signal level will be referred to as a 1 condition in accordance with conventional binary logic designation.

It is to be noted that although a Hall effect device has been described in the preferred embodiment of the invention, any solid state phenomenon, such as magneto-

resistance, would work equally as well as long as the device was able to distinguish between the two flux levels presented by the semicircular shaped cams 50 and 52.

5 The Hall effect devices 58 and 60 are retained preferably by an adhesive material proximate a permanent magnet 74 which extends the full length of the Hall devices. The permanent magnet 74 is polarized with its north pole adjacent the Hall effect devices 58 and 60 10 and its south pole adjacent a flux conducting mounting base member 76. The mounting base member has a lug portion 78 (broken away for clarity in FIG. 2) which is provided with two elongated holes 80 (FIG. 1) which are used to mount the base member 76 to a boss 82 located within the sewing machine base 12. The mounting base member 76 is also provided with an outwardly extending portion 84 which is at a right angle to the base member 76 and is adapted to cooperate with a circular shaped disc member 86 affixed to the shaft 46 by 15 a set screw 88. The disc member 86 is made of a flux conducting material which is similar to the material of the mounting base member 76, the shaft 46 and the cams 50 and 52. The disc member 86 is positioned in close proximity to the outwardly extending portion 84 20 of the mounting base member 76 as is practical, to reduce the air gap therebetween, thereby enhancing the flow of the flux lines 85 provided by the permanent magnet 74.

25 The flux lines 85 emanating from the permanent magnet 74 is shown in FIG. 5. The flux lines essentially follow two paths. The first path is from magnet 74, through base member 76, end portion 84, disc 86, shaft 46, cam 50 and sensor 58, when the air gap between the cam 50 and sensor 58 is minimized. The second path is from the magnet 74, through base member 76, end portion 84, disc 86, shaft 46, cam 52 and sensor 60, when the air gap between the cam 52 and the sensor 60 is minimized.

30 The cams 50 and 52, in the preferred embodiment, are aligned on the shaft 46, as shown in FIG. 4, and provide the digital pulse code indicated thereon as the shaft 46 is rotated counterclockwise.

35 In operation, the digital binary code is generated in the following manner. Assume that as a starting point the low portion 90 of both cams are proximate the Hall effect sensors and that leads 70, 70' and 72, 72' are coupled to a digital control means 44 which may be mounted on a bracket means 45 within the sewing machine base 12, or elsewhere in the sewing machine frame for convenience. A digital control means is described in a copending application Serial No. 376,780, filed July 5, 1973 entitled Sewing Machine Stitch Pattern Generation from Stitch Data Stored in Static Memory, which is assigned to the same assignee as the present invention. The lines 70, 70' are connected to a ground reference and the lines 72, 72' function as the two output signal lines. In this condition the air gap between the cams 50 and 52 and the Hall sensors 58 and 60 are at a maximum; therefore, the flow of the flux lines 85 in the paths described hereinbefore are minimized and both Hall effect devices 58 and 60 assume a low or first condition of 0.3. volts output across leads 70, 72 and 70', 72' or a binary zero, yielding a digital binary code of 00 on lines 72, 72'. As shaft 46 is rotated in a counterclockwise direction the high portion 56 of cam 52 becomes proximate Hall sensor 60, reducing the air gap therebetween and enhancing the flux lines 40

through sensor 60. The sensor 60 changes to a second condition to provide approximately 4 volts across lines 70' and 72', thus, yielding the binary digital code 10 as the shaft 46 is rotated for a length of time related to the shape of the cam 52. When the high portion 54 of cam 50 becomes proximate Hall sensor 58, it changes to its second state also providing approximate 4 volts across leads 70 and 72 yielding a binary 1. Thus, the binary digital code 11 is generated on lines 72, 72' for the time that the high portion 54, 56 of cams 50 and 52, respectively, are proximate sensors 58 and 60, respectively. As the shaft 46 continued to rotate the low portion of cam 52 becomes proximate sensor 60, thereby changing the Hall sensor 60 to its first condition of 0.3. volts output or a binary 0. Thus, the digital binary code 01 is generated on lines 72, 72' until the low portion of cam 50 becomes proximate Hall sensor 58 which causes it to revert to its first condition or 0.3. volts across lines 70, 72 thereby generating a binary 0.

Therefore the binary digital code returns to 0 on line 72 and 0 on line 72' yielding binary digital code 00 on lines 72, 72' for the length of time the low portion 90 of both cams 50 and 52 are proximate the Hall sensors 58 and 60, respectively.

The chart of FIG. 5 indicates the digital pulses obtained just before and after the cams have activated the sensors and, in the preferred embodiment of the invention, the digital binary codes are coupled to the digital control means 44 to enable the control means to provide new bight data at the time of the shaft cycle that it receives a binary digital code of 10, to provide new feed data when it receives a binary digital code 11, and to apply a mechanical clamp to the mechanical portion, not shown, of the digital control means 44, when it receives a binary digital code of 00. Digital code 01 is not used in the preferred embodiment of the invention.

It is to be noted that the sequence of occurrence of the binary code may be used to indicate the direction of rotation of the shaft 46 and, utilizing conventional digital logic, may incorporate this information where required in the digital control means 44. Also it is to be noted that although the preferred embodiment describes binary digitally coded signal pulses the invention is equally applicable to other digitally coded systems.

Hereinbefore has been disclosed a sewing machine equipped with a pulse generator means for providing digitally coded signal pulses related to the position of the sewing machine main-shaft. The pulse generator provides digitally coded binary signals relative to a shaft position that may be used to synchronize a control means with the sewing machine main-shaft.

Having thus set forth the nature of the invention,

what is claimed herein is:

1. In a sewing machine having stitch forming instrumentalities including needle bar actuating means including a main shaft operatively connected to means for controlling said stitch forming instrumentalities, and pulse generator means driven by said main-shaft and providing at least three successively different digitally coded signals related to preselected angular positions of said main shaft upon movement of said main-shaft in one direction of rotation for synchronizing said controlling means with said shaft.
2. A sewing machine according to claim 1 wherein said signals are binary coded.
3. A sewing machine according to claim 1 wherein said controlling means is a digital control means.
4. A sewing machine according to claim 1 wherein said pulse generator means comprises a plurality of position sensing devices responsive to said actuating means and collectively providing a number of coded signals exceeding the number of said sensing devices.
5. A sewing machine according to claim 1 wherein said pulse generator provides binary coded pulses related to the angular position of said main-shaft member and includes two sensor means and two position indicating means.
6. A sewing machine according to claim 1 wherein said sensor means is a Hall device.
7. A sewing machine according to claim 1 wherein said pulse generator for providing digitally coded pulses relating to the angular position of a rotating main-shaft member, comprises:
  - a. a base member;
  - b. permanent magnet means adapted to be affixed to said base member;
  - c. a plurality of sensor means adapted to be mounted juxtaposition said permanent magnet means for providing signal pulses, said sensor means having two stable states; and
  - d. a plurality of position indicating means carried by said rotating member, each having a stepped peripheral circumference cooperating with said sensor means for changing the state of said sensor means in accordance with preselected angular positions of said rotating member.
8. A sewing machine according to claim 7 wherein said base member includes a portion at one end extending outwardly therefrom and said rotating member further includes a circular shaped disc mounted thereon and adapted to cooperate with said outwardly extending base member portion.

ABSTRACT

A sewing machine equipped with a pulse generating means capable of providing digitally coded signal pulses related to the angular position of the sewing machine main-shaft is disclosed. The total number of coded signals exceeds the number of angular position sensors employed. The preferred embodiment utilized two Hall effect devices to provide four binary coded signals responsive to the position of the sewing machine main-shaft.

THE PATENT IS HEREBY AMENDED AS
INDICATED BELOW.

Matter enclosed in heavy brackets appeared in the patent, but has been deleted and is no longer a part of the patent; matter printed in italics indicates additions made to the patent.

AS A RESULT OF REEXAMINATION, IT HAS
BEEN DETERMINED THAT:

Claims 2-6 are cancelled.

Claims 1 and 7 are determined to be patentable as amended.

Claim 8, dependent on an amended claim, is determined to be patentable.

1. **[In a]** *A sewing machine having stitch forming instrumentalities including a needle carrying bar, actuating means including a **main** drive shaft operatively connected **to** thereto, means for controlling said stitch forming instrumentalities to form a stitch pattern, and **pulse generator** means **driven by said main-shaft and providing**, for generating signals detectable by said means for controlling said stitch forming instrumentalities, said signal generating means including a plurality of sensors, each sensor responsive individually to rotation of said drive shaft, said sensors together generating at least three successively different **digitally coded signals***

5 *digital codes each related to a preselected angular **positions** position of said **main** drive shaft, in which the signals detectable by said controlling means constitute a predetermined sequence of occurrence of particular ones of said successively different digital codes, whereby said signals can be generated only upon movement of said **main** drive shaft in one direction **[of rotation]** for synchronizing said controlling means with said shaft.*

10 *7. A sewing machine according to claim 1 wherein said **pulse generator** signal operating means for providing **digitally coded pulses** digital codes relating to the angular position of a rotating **main** drive-shaft member, comprises:*

- 15 *a. a base member;*
- b. permanent magnet means adapted to be affixed to said base member;*
- c. a plurality of **Hall** device sensor means adapted to be mounted juxtaposition said permanent magnet means, each said **Hall** device producing a low or high output voltage in response to the level of magnetic flux from said permanent magnet applied thereto for providing **signal pulses**, said sensor means having two stable states **said digital codes**; and*
- d. a plurality of **magnetic flux** conducting position indicating means carried by said rotating **drive shaft** member, each arranged juxtaposition a respective one of said plurality of **Hall** device sensor means, and each having a stepped peripheral circumference cooperating with said respective **Hall** device sensor means for changing the state of said **sensor means** output voltage in accordance with preselected angular positions of said rotating **drive shaft** member.*
